UNITED STATES PATENT OFFICE.

KARL VIKTOR RUDIN, OF STOCKHOLM, SWEDEN.

ZEROIZING MEANS FOR THE CURVE DISKS OF CALCULATING MACHINES.

Application filed April 10, 1919. Serial No. 289,100.

To all whom it may concern:

Be it known that I, KARL VIKTOR RUDIN, correspondent, subject of the King of Sweden, residing at Stockholm, Sweden, have 5 invented certain new and useful Improvements in Zeroizing Means for the Curve Disks of Calculating Machines (for which I have filed application for patent in Sweden, No. 1151, 1918, filed March 26, 1918), of 10 which the following is a specification.

The present invention relates to certain improvements in zeroizing means for the curve-disks of calculating machines of that kind wherein a setting mechanism is provided 15 with setting wheels and curve-disks, and in which the setting wheels are provided with a variable number of teeth adapted to be actuated by the curve-disks in setting the mechanism for a certain value.

20 An object of the invention is to provide means independent of the above-named means for locking the curve-disks, when set, so as to prevent them from being thrown out of position during the calculating operation, 25 that is to say, during the rotation of the setting mechanism in one direction or the other.

Another object is to provide a zeroizing 30 mechanism by means of which the curve-disks, should not the zeroizing operation be completed, are retained in such way that another setting of the same, and consequently, another calculating operation, is made impossible, until the zeroizing operation is 35 completed.

A further object is to construct the mechanism in such a way that the rotation of the setting mechanism and consequently, another calculating operation, whose result would be 40 incorrect, is made impossible, if the setting of the curve-disks for another calculation be effected or the zeroizing mechanism be actuated prematurely.

45 A further object of this invention is to provide a means easily attachable to a calculating machine having a shaft passing through the setting mechanism of the machine and so connected with the curve-disks that the latter, when set, rotate the shaft in one direction, the shaft being connected with a zeroizing member accessible from the outside of the machine in such a way that the shaft, when actuated by the said member, is rotated in the opposite direction, thus re-setting 50 all the curve-disks in zero position.

An essential feature of my invention and an important object thereof consists in providing means consisting of the connection between the shaft passing through the setting mechanism of the machine and the curve-disks in the form of pins or studs, extending from the shaft, said pins or studs being arranged in the path of pins or studs on the curve-disks, the latter pins or studs being arranged in such a way that the curve-disks during their movement catch the shaft, while the same during the zeroizing operation by means of the zeroizing means is rotated in the opposite direction, during this operation resetting all the curve-disks.

60 A part of the subject matter disclosed herein is disclosed in my copending application filed October 31, 1918, Serial No. 260,550, Patent No. 1,442,004, but is not 65 fully claimed.

With these and other objects in view the invention consists in the construction, combination, details and arrangement of parts hereinafter more fully described and 70 claimed.

75 In the drawings:

Figure 1 is a longitudinal section.

Figure 2 is a cross section looking from the left of Figure 1 of a calculating machine provided with my invention.

80 Figure 3 is a modified form.

Figure 4 is a detail view.

Figure 5 shows from the right in partial section the zeroizing organ proper according to an embodiment of the invention.

85 Figures 6 and 7 show from the side and in front view in partial section the zeroizing organ or unit in accordance with another or modified form of my invention.

90 Figures 8 and 9 show detail views of the mechanism for step-by-step setting of the curve-disks into two different positions.

95 Referring to the drawings, the setting mechanism of the machine consists, as usual, of setting wheels 1 with curve-disks 2, the shaft for setting wheels being indicated by the numeral 14.

100 In the preferred form of my invention the connection between the shaft passing through the setting mechanism of the machine and the curve-disks consists of pins or studs 49, shown to advantage in Figures 2 and 3, extending from the shaft 14 and lying in the way or path of studs 50 arranged on the curve-disks. The shaft 14 is 110

put into the bearing member 54 of the setting wheels 1 and the pins or studs 49 are inserted into perforations therein and may in any convenient manner be attached to the shaft but preferably as shown in Figures 2 and 3, the said pins or studs may be locked by a key 53 sliding in a keyway 52 in the shaft, the pins being inserted into the openings or perforations 51 in the shaft 14, which 10 openings or perforations 51 pass transversely of the shaft. In such a way the pins are reliably secured to the shaft 14.

A sleeve 54 surrounds the shaft 14 and is provided with a transverse slit opposite each 15 pin or stud, of suitable length, preferably one-third or one-fourth the length of the periphery. The surfaces 56 of the recess or slot 55 formed in said way, form in connection with the surface 57 of the hub 58 on each 20 setting wheel, the same being also provided with slits, a limiting surface or surfaces for the movement of the pins or studs.

A pin 59 is suitably, in the same manner as the pins or studs 49, attached to the shaft 25 14 and is actuated by the zeroizing means.

This latter is illustrated in the drawings in two different embodiments. According to the first embodiment shown in Figures 1 to 5, the organ or other member consists of 30 a double armed lever, the one arm 60 of which is loosely mounted upon the sleeve 54, journaled on the shaft 14, and the other arm 61 of which is pivotal in relation to the former arm 60 and provided with a shoulder or the like 62, adapted to mesh with the pin 59 or any other part extending from the shaft 14, when the arm 61 is in its operative position. The arm 61 is pivotally arranged about the shaft 63 and is actuated by a 40 spring 64 which normally holds the arm in resting position. In this position the arm permits the free passage of the pin 59 during the calculating.

The arm 61 is provided with a handle 65 45 in order to make it possible to manipulate the same. In manipulating the arm 61, viz, pressing the handle 65 upwards, the shoulder 62 is turned downwards so as to mesh with the pin 59 (Fig. 5). In further turning the 50 arm 61 together with the arm 60 clockwise the shaft 14 is likewise, by means of the pin 59, turned clockwise and the curve discs are reset to zero.

In order to limit the extent of movement 55 of the arm 61 in relation to the arm 60 one of the arms, for instance, preferably the arm 61, is provided with a pin or stud 66, entering into and running in a recess 67 of the other arm, for instance 60 when the first 60 named arm is manually moved against the resistance of the spring.

It is evident, that the parts limiting the movement of the arm 61 may also be arranged in another way. The recess 67 may 65 for instance consist of a slot or the like, and

the pin 66 of a shoulder or the like, or another surface being able to push against the surface of the other arm.

The movement of the arm 60 or rather of the zeroizing member as a whole, is limited by the medium of the support 68, against which the arm 60 is caused to push. The zeroizing member as a whole is actuated by a spring 69 tending to move the organ back into its resting position. 75

In a modified form shown in Figs. 6 and 7, there is a difference from that already described in that the different parts of the organ are arranged as follows: The shoulder 62 is replaced by a pin or stud 62'. Further, the spring 64 is here so arranged that it is inserted in a recess 70 of the arm 60, whereby the one end of the spring rests against the bottom of the recess, while the other end of the spring rests against a pin 71 arranged in the recess and pressing against the arm 61 and holding the same in its resting position, that is to say, in such a way that the pin 62' is out of the way of the pin 59. The movement of the arm 61 90 in relation to the arm 60 is thus limited so that when the arm 61 is in its extreme position its surface 72, abuts the opposite surface of the arm 60, shown better in Fig. 6. In the extreme position shown in Fig. 6, the surface 73 of the arm 61 abuts the opposite surface of the arm 60. 95

The zeroizing means may also consist of a knurled knob 61^a handle or the like placed outside the machine and attached directly to 100 the shaft 14 as illustrated in Fig. 3. In such case the shaft 14 is rotatable directly and all intermediate means are superfluous.

More particularly describing this structure the known arrangement is constructed in such a way that according to Fig. 4 the member 2 is provided with teeth 76 in which teeth a pawl 75 is yieldingly held by a spring 77, as better shown in Figure 2. Normally this pawl cannot be moved from engagement with the teeth because of a block 84 in its path, in the form of a slotted shaft which shaft is movable by a lever 36 into the two positions, one shown in Fig. 8, and the other shown in Fig. 9. The lever 36 is provided with a lug 86 seating into a recess 42 in the casing, thereby permitting the turning of the member 2 only at a time when the said mechanism is in the position shown in Fig. 9, that is to say when the lug 86 is in the recess 42. The outward movement of the lever 36 into the recess 42 causes the said lever 36 to press against a plunger or pin 40 which is yieldingly held outward by a spring 40^a and which spring is normally pushed inward by a spring 40^b pushing a plunger 40^b mounted upon a crank 40^c for actuating the calculating machine. 110

Thus when the plunger 40^b is in a predetermined position of the crank 40^c pushing against the plunger 115 120 125 130

40, the said lever 36 is forced out of engagement and into the slot 42, but otherwise and unless the said crank is in the said position as shown in Fig. 1, the lever 36 will be normally in the position shown in Fig. 8, thereby preventing the turning of the members 2 because of the locked position of the pawls 75 in the teeth 76.

More particularly describing the device 10 actuated in such a way by the zeroizing organ that the curve disks during the proper zeroizing are released from the pawls 75, said pawls, one for each curve disk, are arranged upon a shaft 74, shown in Figs. 2, 15 5 and 7, passing through the setting mechanism, whereby said pawls preferably elastically engage into the toothed ring or the like 76 for each curve disk shown in Figs. 2, 8 and 9.

20 The shaft 74 for the pawls 75 has at one end an arm 78 provided with a pin or stud 79, shown in Figs. 6 and 7 by means of which the shaft 74 is actuated by the zeroizing organ. This is attained inasmuch as 25 the pin or stud 79 may during the zeroizing operation slide over a curved surface or the like 80 on the zeroizing organ whereby the arm 78 will be moved out to such position, as to allow the engagement of the pawls 75 with the curve-disks. Hence the moving 30 back of the curve-disks into the zero position is facilitated, and a step-by-step setting of the curve-disks made impossible, should the new calculation be performed before 35 completing the zeroizing operation.

During the whole zeroizing operation the shaft 84 has the normal position shown in Fig. 9 in which it allows the free movement of the pawls 75. After having performed 40 a new setting operation and a new turning of the setting mechanism is to be performed the indenture 86 is pressed out of the recess 42 during the rotation of the crank, which results in a displacing of the shaft 45 84 to the left side from the position shown in Fig. 8. In this position the pawls 75 cannot be rotated, and on account of this the curve-disks cannot be moved out of their set positions during the rotation of the setting 50 mechanism. When moving the setting mechanism back into its initial position the notch or indenture 86 is again moved into its recess by means of the crank and the bar 40 actuated by the same. The pawls are thus 55 released and permit a new setting of the curve-disks.

It is to be noted that the setting mechanism or the crank cannot be rotated during the zeroizing operation. This is attained 60 by the pawls 75 being during this operation locked in their outermost position in which they engage into the recesses 85 of the shaft 84, thus preventing the latter from being displaced to the left. Thus the notch 86 65 cannot be moved out of the recess 42, and

the setting mechanism or the crank cannot be rotated.

What I claim is:—

1. In a calculating machine, in combination with curved disks and setting wheels, 70 zeroizing means mounted for manual movement, means to return the zeroizing means to normal position, pawls to engage teeth of the curve disks, a shaft on which said pawls are pivotally mounted, said shaft and pawls having means to permit limited pivotal movement of said pawls on said shaft, and said shaft being operated by the zeroizing means to disengage the pawls from the curved disk teeth during zeroizing. 80

2. In a calculating machine of the class described, in combination with curved disks and setting wheels, pawls to engage teeth of the curved disks and permit step-by-step setting thereof, and zeroizing means for the 85 curved disks, said zeroizing means also serving to disengage the pawls from the curved disk teeth during zeroizing.

3. In a calculating machine of the class described, in combination with curved disks 90 and setting wheels, pawls to engage teeth of the curved disks and permit step-by-step setting thereof, zeroizing means for the curved disks, said zeroizing means also serving to disengage the pawls from the curved 95 disk teeth during zeroizing, and means to prevent or permit operation of the pawls at will.

4. In a calculating machine, a calculating 100 rotor, an arcuate portion of said rotor provided with serrations, a pawl adapted to engage with said serrations, and means for locking said pawl in its movement from serration to serration when said calculating member is in a predetermined position. 105

5. In a calculating machine, a plurality of rotors provided with curved discal surfaces for the usual calculating operation, an annular pivotal mount for said rotors, a crank for turning said rotors, a pin projecting 110 through said rotors eccentric said pivotal mount, a pawl for engagement with said discal members, said pin in the path of said pawl in its movement from disengagement with said members, means for longitudinally sliding said pin, and recesses in said pin to permit the escape of said pawl when said pin is in a predetermined longitudinal position. 115

6. Means for zeroizing the curve-disks 120 after completed calculating operation in calculating machines having setting wheels provided with a variable number of teeth, said means consisting of a shaft passing through the setting mechanism of the machine, characterized by the connection between the curve-disks and the shaft consisting of pins or studs extending from the shaft, said pins or studs being brought in the path of stops upon the curve-disks in such way that the 125 130

curve-disks during their setting movement catch the shaft while the latter during the zeroizing operation is by means of the zeroizing member caused to rotate in the opposite direction and during this movement by means of the pins or studs and the stops move all the curve-disks back into their zero position.

7. In a device according to claim 6, the arrangement that the shaft passing through the setting mechanism of the machine consists of a shaft put into the usual sleeve or bearing member 54 for the setting wheels.

8. In a zeroizing device according to claim 5 and the arrangement that the pins or studs 49 extending from the shaft pass through the hub of the setting wheel 1 or other sleeves or rings mounted upon the shaft, said sleeves or rings being provided to a certain length of their periphery, suitably $\frac{1}{4}$ or $\frac{1}{2}$ of the same, with transverse slots whereby the surfaces of the slots serve to limit the movement of the pins or studs.

9. In a zeroizing mechanism according to claim 7, the arrangement that the pins or studs 49 are put into transversal openings 51 of the shaft 14 and provided with grooves or recesses running in the longitudinal direction of the shaft, said grooves or recesses corresponding with a key groove 52 arranged in the shaft, a locking bar or such like 53 being put into said key groove and grooves or recesses in order to securely lock the pins or studs.

10. In the zeroizing mechanism according to claim 7, the arrangement that the shaft, for instance the shaft 14, passing through the setting mechanism of the machine is provided with a pin 59 preferably attached in the same way as the pins or studs 49, said pin being directly actuated by the zeroizing organ.

11. In a zeroizing mechanism according to claim 7, the arrangement that the zeroizing organ consists of a double armed angle lever, the one arm 60 of which is loosely mounted upon a sleeve 54 surrounding the shaft, say 14, passing through the setting mechanism of the machine, and the other arm 61 of which is pivotable in relation to the former and provided with a shoulder, pin or such like 62 adapted to be brought into engagement with the pin 59 or any other part extending from the shaft in the operative position of the arm.

12. In a zeroizing organ as claimed in claim 11, the arrangement that the arm 61 of the organ, adapted to actuate the pin 59 is actuated by a spring 64 in such way that

the arm normally is retained in its resting position, in which it allows the free movement of the said pin during the counting.

13. In a zeroizing organ as claimed in claim 11, the arrangement that the one arm of the organ is provided with a shoulder or surface adapted to, by the rotation of the other arm in relation to the former, stop the former in a certain end position.

14. In a zeroizing organ according to claim 11, the arrangement that the organ as a whole is actuated by a spring moving the same back into its initial position.

15. An arrangement for setting the curve-disks step-by-step and comprising pawls to engage internal teeth of the curve-disks, a pivotal axis for said pawls passing through the setting mechanism, springs to hold said pawls normally in engaged position, a shaft provided with an arm, and zeroizing means to actuate said arm to bring the pawls out of mesh with the curve-disks during the zeroizing and thereby to facilitate their movement back into their zero position and to make their step-by-step setting impossible.

16. An embodiment of the arrangement according to claim 15, including an arm 78 provided with a pin or stud 79 adapted to slide along a curved surface or such like 80 of the zeroizing means, said zeroizing means also having means whereby the arm 78 with the shaft 74 is pressed out of its position after zeroizing is complete allowing the engagement between the pawls 75 and the curve-disks.

17. In a calculating machine, in combination with curved disks and setting wheels, zeroizing means mounted for manual movement, means to return the zeroizing means to normal position, pawls to engage teeth of the curve disks, a shaft on which said pawls are pivotally mounted, said shaft having an arm actuated by the zeroizing means and also being provided with a pin for each of the pawls, and each pawl having a recess to receive said pin to enable the pawl to be turned independently of the shaft during its engagement with the curved disks and to be caught by the shaft by means of the recess and pin during the rotation of the shaft, by the operation of the zeroizing means upon the said arms.

In testimony whereof I affix my signature in presence of two witnesses.
